END STOP FOR SEPARABLE FASTENERS

Davis Marinsky, Bronx, N. Y., assignor to White-
hall Patents Corporation, New York, N. Y., a
corporation of New York

Application September 10, 1935, Serial No. 39,909

5 Claims. (Cl. 24—205)

This invention relates to separable slide fasteners and particularly to the provision of an improved end stop for limiting the movement of the slider or rider longitudinally of the stringers 5 in one direction; and the object of the invention is to provide an end stop of the class described with a finger piece or pull movably supported in connection therewith to facilitate the movement of the slider longitudinally of the stringers 10 in the operation of closing the fastener; a further object being to provide an end stop in the form of a clip having means passed through the fastener stringers for securing the same thereto and for coupling said stringers together 15 in close proximity to each other, said end stop being also fashioned to receive and support the finger piece or pull in connection therewith; and with these and other objects in view, the invention consists in a device of the class and for the 20 purpose specified, which is simple in construction, efficient in use and which is constructed as hereinafter described and claimed.

The invention is fully disclosed in the following specification, of which the accompanying 25 drawing forms a part, in which the separate parts of my improvement are designated by suitable reference characters in each of the views, and in which:

Fig. 1 is a plan view of a part of a fastener 30 showing one of my improved end stops mounted in connection therewith.

Fig. 2 is a view similar to Fig. 1 on an enlarged scale and with part of the construction 35 broken away.

Fig. 3 is a section on the line 3—3 of Fig. 2.

Fig. 4 is a rear view of the construction shown in Fig. 2.

Fig. 5 is a view similar to Fig. 2 showing a modification.

Fig. 6 is a view similar to Fig. 2 showing another modification.

Fig. 7 is a rear view of the construction shown in Fig. 6; and,

Fig. 8 is a section on the line 8—8 of Fig. 6.

together by a coupling block or clip 15, which forms an end stop limiting movement of the slider 13 in one direction on the stringers. The clip or stop member 15, in the construction shown, comprises a cup-shaped casing, opposed 5 side walls of which are provided with inwardly directed prongs 16 adapted to be passed through the top of the stringers and folded around the enlarged or beaded edges 10a, 11a thereof in securing the stop member 15 in position. 10

The side walls of the member 15 intermediate the prongs 16 are provided with notches or recesses 17 to receive a comparatively straight bar portion 18 of a ring or loop 19 to provide a finger piece or pull facilitating the operation of the 15 fastener. The finger piece or pull 19 is, as stated, in the form of a ring or loop and is capable of swinging movement from the position shown in Fig. 1 to a position where the loop would rest upon the surface of the attached 20 coupling links 12. In use, the finger piece 19 is simply raised sufficiently for engagement by the fingers of a hand in the operation of moving the slider 13 away from the end stop 15 in closing the separable fastener device. 25

In Fig. 5 of the drawing, I have shown a slight modification which consists in simply substituting for the ring or loop finger piece 19, a flat plate 20 which may be of any desired contour or design. The plate is apertured at one 30 end as seen at 21 to provide the coupling or pivot bar 22, and the other end portion of the plate is apertured as seen at 23 to insure a positive grip upon said plate by the fingers of a hand. The plate or finger piece 20 may be 35 swung in connection with the end stop the same as the finger piece 19, the end stop 15 being of the same construction as that shown in Figs. 1 to 4 inclusive.

In Figs. 6, 7 and 8 of the drawing, I have 40 shown another modification wherein an end stop 24 is provided which differs from the end stop 15 in that the notches or recesses 17 are eliminated, and instead, the top wall of the end stop is provided with an aperture 25 forming 45 a seat for one spherical member 26 at an end of a flexible pull chain 27, the other free end having an enlarged spherical member 28. The flexible chain 27 forms a finger piece performing the same functions and operations as the 50 finger pieces 19 and 20. The end stop 24 has prongs 29 on opposite side walls, which prongs engage the tapes of the stringers and are of the same general construction as the prongs 16 except that they are made sufficiently long to 55

overlie the end ball or spherical member 26 of the chain 27 to retain said chain against displacement from the end stop.

The advantages of my improved end stop construction consist first, in providing a practical as well as strong and durable finger piece which may be engaged by the fingers of one hand in the operation of closing the fastener; and secondly, the finger piece or pull may be mounted in position and coupled with the fastener in the operation of attaching or coupling the end stop with the tapes of the stringer, thus eliminating the operations which would otherwise be required to couple or attach a finger piece to the separable fastener. In other words, aside from the cost of producing the particular finger piece employed, there is no additional cost required in its attachment to the fastener, aside from the operation of placing it in position.

20 The particular slide fastener disclosed is merely illustrative of one type of fastener which may be employed, and the structure of the tape, links and slider may be varied to suit the desires or fancy of the manufacturer or the customer for whom the fastener devices are made. In fact, this is also true as to the contour and style of finger piece employed in conjunction with the end stop.

Having fully described my invention, what I claim as new and desire to secure by Letters Patent, is:

1. An end stop for separable fasteners of the class described comprising a stop plate having prongs projecting from one surface thereof for attachment to suitable supports, a finger piece having a portion disposed upon said plate and retained against displacement therefrom by said prongs when attached to the supports, the prongs of said plate being arranged in pairs at opposite side edges thereof, and said finger piece including a bar pivotally supported between the prongs of each pair.

2. An end stop for separable fasteners of the class described comprising a cup-shaped sheet metal member, opposed side walls of which are extended and cut out to form pairs of projecting prongs with a socket or recess in said walls

intermediate the prongs, and a finger piece including a bar transversing said member and having a bearing in the socket intermediate the pairs of prongs.

3. An end stop for separable fasteners of the class described comprising a cup-shaped sheet metal member, opposed side walls of which are extended and cut out to form pairs of projecting prongs with a socket or recess in said walls intermediate the prongs, a finger piece including a bar transversing said member and having a bearing in the socket intermediate the pairs of prongs, and said prongs providing means for attaching said cup-shaped body to suitable supports and for retaining the finger piece 15 against displacement from said body.

4. An end stop for the stringers of separable fasteners of the class described comprising a cup-shaped body, two opposed walls of which are fashioned to form projecting prongs adapted 20 to be passed through the stringers of a fastener to permanently couple the stringers together at one end of the fastener, said prongs being folded and compressed upon the stringers in securing said end stop thereto, said cup-shaped body 25 when attached to the stringers forming a chamber therein, and a finger piece having a part movably supported in said chamber and retained against displacement from said body when attached to said stringers. 30

5. An end stop for the stringers of separable fasteners of the class described comprising a cup-shaped body, two opposed walls of which are fashioned to form projecting prongs adapted 35 to be passed through the stringers of a fastener to permanently couple the stringers together at one end of the fastener, said prongs being folded and compressed upon the stringers in securing said end stop thereto, a finger piece movably coupled with the end stop and retained against displacement therefrom when attached to said stringers, and said finger piece including a portion pivotally supported in connection with the end stop and projecting through said opposed 40 walls thereof. 45

DAVIS MARINSKY.
